UNITED STATES PATENT OFFICE.

LOUIS H. MORIN, OF NEW YORK, N. Y., ASSIGNOR TO IDEAL CUP CORPORATION, OF BROOKLYN, NEW YORK, A CORPORATION OF NEW YORK.

DISPENSING DEVICE.

Application filed December 17, 1926. Serial No. 155,395.

The invention relates to dispensing devices and more particularly to devices of this character which are designed for dispensing paper receptacles, such as paper cups and the like, in individual successive steps from a stack of such receptacles contained in the device. The object of the invention is to provide a simple dispensing mechanism whereby the cups will be positively ejected in individual sequence from the lower end of the stack in an efficient manner and whereby the remaining stack of cups will be retained within the device. Other more specific objects will appear from the description hereinafter and the features of novelty will be pointed out in the claims. It will be understood that the term "cups" is used herein in a broad sense to include equivalent receptacles adapted to be dispensed from a device such as is herein shown and described.

In the accompanying drawings which illustrate an example of the invention without defining its limits, Fig. 1 is an exterior elevation of the device partly in section; Fig. 2 is an elevation looking at right angles to Fig. 1; Fig. 3 is a fragmentary section on the line 3—3 of Fig. 2; Fig. 4 is a similar view showing the parts in a different position; Fig. 5 is a detail section on the line 5—5 of Fig. 3; Fig. 6 is a detail plan view, and Fig. 7 is a detail section on the line 7—7 of Fig. 4.

The device comprises a body 10 of suitable dimensions and shape generally cast in a suitable material in accordance with the particular type of receptacles for which the device is designed. In the illustrated example, the body 10 is hollow and is of cylindrical form with open inlet and exit ends as clearly shown in Figs. 3, 4 and 5 of the drawings. A container 11, preferably consisting of a tube of glass or other transparent material, having its upper end closed, is fitted upon said body and projects upwardly therefrom as illustrated in Figs. 1 and 2; in the preferred arrangement the body 10 is reamed out to form an internal annular shoulder 12 upon which the open lower end of the container 11 rests. The body 10 is provided near its exit end with a slit 13 extending upwardly and outwardly from the inner surface *a* and including a grooved portion 14, said slit 13 and its grooved portion 14 communicating with the bore 15 of a boss 16 located externally upon the body 10 as shown in Fig. 2; the axis of the bore inclines

upwardly and outwardly relatively to the major axis of the body 10 in axial registry with the slit 13 and its groove 14 as illustrated in Figs. 1, 3 and 4. A plunger 17 is slidably mounted in the bore 15 and is preferably cup shaped to receive the one end of a spring 18, the other end of which engages the bottom of the bore 15 for maintaining the plunger in and returning it to its outermost position. An ejecting finger 19 is pivotally connected at 20 with the plunger 17 and projects lengthwise of the bore 15 into the groove 14 and slit 13. The free end of the finger 19 is preferably curved in a direction transverse to its length, as indicated at 21, and terminates in an ejecting nose 22, the free end of which, in the normal position of the ejecting means lies approximately flush with the inner surface *a* at the slit 13 as shown in Fig. 1. The ejecting finger 19 includes a compound slot 23 having an inner end portion *b*, extending transversely to the direction of movement of the plunger 17, or in approximately the same direction as the free end portion of the finger 19, and a continuing portion *c* extending lengthwise of the finger 19 and preferably at a slight inclination to the length thereof as shown in Figs. 3 and 4. A fixed pin 24 projects across the slit 13 and through the slot 23 for the purpose to be more fully set forth hereinafter. The body 10 is provided internally with a supporting means which, in the illustrated example, comprises two lugs 25 located upon opposite sides of the slit 13 and projecting inwardly from the inner surface of the body 10, as shown in Fig. 3; if desired, the supporting means may further include a projection 26 extending inwardly from the inner surface of the body 10 at a point diametrically opposite to the slit 13 as shown in Fig. 6.

In practice, a supply of containers or paper cups 27 arranged in the form of an inverted stack are contained within the container 11 with the rim of the lower terminal cup of the stack resting upon the lugs 25 as shown in Fig. 3 and the periphery of said rim in frictional engagement with the projection 26 if the latter forms a part of the device; with this arrangement, the lugs 25 or their equivalent project beneath and engage the rim of the lower terminal cup while the periphery of the rim of said lower terminal cup is frictionally engaged by the

110

projection 26 so that the latter cooperating with said lugs supports the stack or container of cups in an upright position within the body 10 and the container 11 in the manner illustrated in Figs. 1 and 2. It will be noted that the nose 22 of the finger 19, in the normal position of the parts, is located in registry with the space between the rim of the lower terminal cup of the stack and 10 the next succeeding cup thereof as shown in Fig. 1. To eject a cup from the dispensing device, the plunger 17 is depressed against the tension of the spring 18 and accordingly causes the nose 22 of the finger 19 to be 15 adjusted inwardly through the slit 13; during this adjustment of the parts, the finger 19 moves lengthwise of the groove 14 and is maintained thereby against tilting sideways. Because of the curved form of the inner end 20 of the finger 19 and by reason of the compound form of the slot 23 in cooperation with the pin 24, the finger 19 is given a compound movement. In other words, the nose 22 of the finger describes an initial movement which is substantially at right angles 25 to the axis of the body 10 and brings it into contact with the terminal cup at the lower end of the stack as shown in Fig. 3, and then moves downwardly in a direction approximately parallel with said axis in the manner indicated in Fig. 4; because of this compound movement the nose 22 first presses the terminal cup of the stack inwardly beyond the lugs 25 and then downwardly and thereby releases said terminal cup from the stack 30 and permits it to drop through the exit end of the body, these steps in the ejecting operation being clearly shown in Figs. 3 and 4. At the same time the nose 22 will extend 35 beneath the rim of the next succeeding cup of the stack to prevent it from dropping out of the device and as the plunger 17 resumes its normal position permits the succeeding cup which is now the terminal cup of the stack to come to rest upon the lugs 25. For convenience a hook 28 may be provided to receive the ejecting cup as it drops from the body 10 as shown in Fig. 2.

The device is extremely simple in construction and is positive in action so that the cups are positively ejected in individual sequence as they successively become the terminal cup at the lower end of the stack and at the same time the remaining cups of the stack are maintained in the device against unintentional removal therefrom.

Various changes in the specific form shown and described may be made within the scope of the claims without departing 60 from the spirit of my invention.

I claim:

1. In a dispenser for paper cups, the combination of a hollow body having open inlet and exit ends and provided with a vertically arranged slit near its exit end, a

container removably fitted upon said body and projecting upwardly therefrom for containing an inverted stack of cups, supporting lugs projecting inwardly from the inner surface of said body in spaced relation upon opposite sides of said slit and adapted to project beneath and engage the rim of the lower terminal cup, means upon the inner surface of said body adapted to frictionally engage the periphery of said rim of the lower terminal cup and cooperating with said lugs to support the stack of cups, a boss located externally upon said body and having a guide bore communicating with said slit, the axis of said bore inclining upwardly and outwardly relatively to the major axis of the body, a plunger slidably mounted in said bore, an expelling finger pivotally connected with said plunger and adapted to be projected through said slit and retracted thereby, said finger being provided with a compound slot having an inner end portion extending transversely to the direction of movement of said plunger and a continuing portion extending lengthwise of said finger, and a fixed pin projecting across said slit and through said slot whereby said finger initially moves inwardly to force the terminal cup inwardly beyond said lugs and then downwardly to release said terminal cup from the stack and permit it to drop through the exit end of said body.

2. In a dispenser for paper cups, the combination of a hollow body having open inlet and exit ends and provided with a vertically arranged slit near its exit end, a container removably fitted upon said body and projecting upwardly therefrom for containing an inverted stack of cups, supporting lugs projecting inwardly from the inner surface of said body in spaced relation upon opposite sides of said slit and adapted to project beneath and engage the rim of the lower terminal cup, means upon the inner surface of said body adapted to frictionally engage the periphery of said rim of the lower terminal cup and cooperating with said lugs to support the stack of cups, a boss located externally upon said body and having a guide bore communicating with said slit, the axis of said bore inclining upwardly and outwardly relatively to the major axis of the body, a plunger slidably mounted in said bore, and means operated by said plunger through said slit to initially force the terminal cup inwardly beyond said lugs and to subsequently force said terminal cup downwardly to permit it to drop through the exit end of said body.

3. In a dispenser for paper receptacles, the combination of a hollow body having open inlet and exit ends and provided with an aperture near its exit end, supporting means within said body upon opposite sides of said aperture for engaging the lower terminal

receptacle to support an inverted stack of said receptacles in said body, and ejecting means comprising a plunger and an expelling finger pivotally connected with said plunger and compressible thereby in a direction diagonal to the major axis of said stack of receptacles, and means whereby said finger is given an independent inward movement during the diagonal depression of said

finger to force said terminal cup inwardly 10 from said supporting means and downwardly with respect thereto to permit said terminal cup to drop through the exit end of said body.

In testimony whereof, I have hereunto set 15 my hand.

LOUIS H. MORIN.
